United States Patent Office

Des. 209,042
Patented Oct. 31, 1967

209,042

CAT HOUSE

James Davidson Harum, 9100 SW. 85th St.,
Miami, Fla. 33156

Filed Sept. 23, 1966, Ser. No. 4,004

Term of patent 3½ years

(Cl. D12—2)

FIG. 1

FIG. 1

FIG. 2

FIG. 3

FIG. 4

FIG. 1 is a perspective view of a cat house showing my new design.

FIG. 2 is a side elevation thereof.

FIG. 3 is a top plan view thereof.

FIG. 4 is a bottom plan view thereof.

The sides not shown in FIG. 1 are the same as that shown in FIG. 2.

I claim:

The ornamental design for a cat house, as shown and described.
